UNITED STATES PATENT OFFICE.

JOHN D. RIORDAN, OF HANNIBAL, MISSOURI.

HUB-LINER.

1,289,544.

Specification of Letters Patent. Patented Dec. 31, 1918.

Application filed July 6, 1918. Serial No. 243,595.

To all whom it may concern:

Be it known that I, JOHN D. RIORDAN, a citizen of the United States, residing at Hannibal, in the county of Marion and State of 5 Missouri, have invented new and useful Improvements in Hub-Liners, of which the following is a specification.

This invention relates to new and useful improvements in hub liners and the principal object of the invention is to provide improved means for securing the liner to the bearing box.

Another object of the invention is to provide a device of this character which is simple and durable in construction, reliable and efficient in operation and one which can be manufactured and placed upon the market at a minimum cost.

The invention also consists in certain other 20 features of construction and in the combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views and in which:—

30 Figure 1 is a rear view of a bearing box with my invention in place thereon.

Fig. 2 is a side view of the invention.

Fig. 3 is a front view thereof.

As shown in these views the bearing box 1 35 contains the usual axle supporting members, not shown and the oil cellar 3. 4 represents the hub liner which is secured in any suitable manner to the carrying plate 5. This plate covers the front face of the bearing 40 box, and it is provided with side flanges 6

and a top flange 7. The upper corners of the plate are cut off as at 8 so that the top flange is of relatively small length. This flange is provided with an opening 9 to receive a set screw which engages the top of 45 the box and the side flanges are provided with rearward extensions 10 at their lower ends and each of these extensions is provided with a hole 11. The flanges will snugly engage the sides and top of the bearing box and the openings 11 are so arranged that they will receive the bolt 12 which holds the oil cellar in position. In this way it is not necessary to bore holes in the box as the liner is held in position by the cellar bolt 55 and the set screw in the top flange. The liner may be made of any suitable material such as brass or babbitt.

The drawing shows the liner secured to the plate by means of the screw bolts 13. 60

It is thought from the foregoing description that the advantages and novel features of my invention will be readily apparent.

I desire it to be understood that I may make such changes in the construction and 65 in the combination and arrangement of the several parts, provided that such changes fall within the scope of the appended claim.

What I claim is:—

The combination with a bearing box and 70 its oil cellar, of a flanged plate covering the front of the box with its flanges engaging the sides and top thereof, a liner carried by said plate, a set screw carried by the top flange and engaging the top of the box and 75 openings in the side flanges for receiving the cellar bolt.

In testimony whereof I affix my signature.

JOHN D. RIORDAN.
